DOORBELL ESCUTCHEON

Lawrence P. Mellyn, Gloucester, R.I., assignor to
General Electric Company

Filed Aug. 31, 1973, Ser. No. 393,456

Term of patent 14 years

Int. Cl. D8—09

U.S. CL. D8—182

FIG. 1

FIG. 2

FIG. 3

FIG. 4

FIG. 5

FIG. 6

FIG. 7

© General Electric Company 1976. The drawings of this patent document contain material to which a claim of copyright is made. The copyright owner, assignee herein, has no objection to the duplication of the patent drawing but reserves all other copyright rights whatsoever. A certified copy of the certificate of copyright registration as registered by the U.S. Copyright Office is in the file of the application of this patent.

FIG. 1 is a perspective view of a doorbell escutcheon embodying my new design;

FIG. 2 is a front elevational view thereof;

FIG. 3 is a back elevational view thereof;

FIG. 4 is a side elevational view thereof;

FIG. 5 is a side elevational view of the opposite side thereof;

FIG. 6 is a top plan view thereof; and
FIG. 7 is a bottom plan view thereof.

I claim:

The ornamental design for a doorbell escutcheon, as shown and described.
